CLAIM

The ornamental design for a magnetic ring, as shown and described.

DESCRIPTION

FIG. 1 is a perspective view of a magnetic ring showing my new design;

FIG. 2 is a front view thereof;

FIG. 3 is a rear view thereof;

FIG. 4 is a right side view thereof;

FIG. 5 is a left side view thereof; and,

FIG. 6 is a top view thereof, a bottom view being a mirror image of the top view.

The stippled shading depicts magnetic portions and a contrast in appearance between the remainder of the surfaces, and forms part of the claimed design.
